UNITED STATES PATENT OFFICE.

FREDERICK E. KIEFER, OF BRIDGEPORT, CONNECTICUT.

DESIGN FOR A PAPER-HOLDER.

SPECIFICATION forming part of Design No. 23,446, dated July 10, 1894.

Application filed June 1, 1894. Serial No. 513,210. Term of patent 3½ years.

To all whom it may concern:

Be it known that I, FREDERICK E. KIEFER, a citizen of the United States, and a resident of Bridgeport, in the county of Fairfield and

5 State of Connecticut, have invented a certain new and original Design for Paper-Holders, of which the following is a specification.

This invention relates to a design for a paper or letter holder as shown in the accompanying illustration wherein the figure shows a perspective view of the holder.

The leading feature of this design is in the general oblong outline, together with the ornamented surface of the main plate at the top and bottom thereof, also the tapering shape and ornamentation of the finger.

Upon the accompanying drawing, which forms a part of this specification, 1 represents the main plate which is provided with screw-holes and is enlarged at the upper and lower portions thereof.

2 represents scalloped edges of the plate and 3 sunken, ornamented surfaces of special formation upon the top and bottom face of the plate.

Upon the finger 4 is a rib 5 which follows the edge of the finger from above its center to the lower end thereof, where said rib broadens inwardly and forms a point 6 upon the flat surface of the finger.

Having thus described my invention, I claim—

The design for a paper holder substantially as herein shown and described.

Signed at Bridgeport, in the county of Fairfield and State of Connecticut, this 26th day of May, A. D. 1894.

FREDERICK E. KIEFER.
